UNITED STATES PATENT OFFICE

2,124,970

CLOSING AND LOCKING DEVICE FOR OVER-
HEAD GARAGE DOORSWallace E. Bagley, Glenside, Pa., assignor to
Huck-Gerhardt Company, Inc., Philadelphia,
Pa.Original application March 25, 1936, Serial No.
70,736. Divided and this application June 5,
1936, Serial No. 83,616

1 Claim. (Cl. 292—40)

This invention relates to a manually operated closing and locking device for overhead garage doors and, more particularly, to a divisional application of a previously filed application, Serial Number 70,736 dated March 25, 1936, and has for its primary object the incorporation in a locking device of a plurality of types of closing elements whereby the door may be more effectively and positively forced into closed position with the door frame and locked in such position.

An object of the invention resides in the use of a combination of closing elements which co-operate in a new and effective manner to give the required movements to the door panels in a plurality of directions towards the door frame upon the door reaching its closed position, said closing elements being capable of being locked for holding the door in closed position.

A feature of the invention resides in the novel manner of designing the parts of the manually operated closing device whereby any irregularities in construction or assemblage of the parts, or irregularities in the closing movements of the door panels, may be compensated for to assure full closing of the door against its door frame.

Another feature of the invention resides in a design of closing device in which the parts co-function to move the door panels horizontally towards the door frame, and vertically towards the ground base of the door frame, whereby the door is assured of close contact with its frame and with the ground base.

With these and other objects in view, the invention will be better understood from the following detailed description, taken in conjunction with the accompanying drawings, wherein:

Figure 1 is a side elevation of the door.

Figure 2 is a perspective view of a part of the locking device.

Figure 3 is a vertical sectional view through the closing and locking device.

Figure 4 is a cross sectional view of a part of the closing and locking device.

Figure 5 is a front elevation of the keeper plate.

Figure 6 is an edge elevation of the keeper plate and associated elements.

Figure 7 is a cross sectional view of the door.

Figure 8 is a horizontal detail sectional view through the keeper plate and associated elements.

Again referring to the drawings, illustrating one of the many constructions of the invention, the numeral 1 designates the door frame of a garage, or any suitable enclosure, the frame 1 resting upon a ground base 2. Associated with

the door frame is a door 3 consisting of a plurality of hinged panels 4, the number of panels depending upon the area of the opening formed by the door frame 1.

These panels are provided with overlapping flanges 4a at their abutting edges and, further, the abutting edges of the panels are hinged together by hinges 5 which are preferably of the improved type illustrated in copending application filed March 19, 1936, Serial Number 69,649, and including rollers 22 adapted for movement in guide tracks 24 and 25, supported by frames 23, and each shaped and constructed to have a lower vertical inclined portion 26, a vertical straight portion 27, a continuation of the inclined portion 26; an intermediate curved portion 28, a continuation of the straight portion 27; and a horizontal portion 29 a continuation of the curved portion 28, as more clearly set forth and described in copending application Serial Number 70,736, filed March 25, 1936.

Associated with the inclined portion 26 and attached to the lower panel 34 is an automatic closing device 35 which consists of a clip 44 carrying a roller 45 that is positioned to have a wedging action with the inclined portion 26 when the bottom panel 34 reaches its closed position, resulting in the panel 34 being forced towards the frame 1. The intermediate panels of the door are associated with a locking device which not only functions to force and lock the door in closed position, but to operate with the closing device 35 to move the door downwardly as well as horizontally, to assure the closing thereof in tight position with the door frame and with the ground base.

The locking device 41 consists of a pair of latch bolts 55, one for each vertical edge of the door and each having a double cam action with the tracks so that the set of door panels may be given the desired horizontal and vertical movements in the actuation of the locking device 41. Each bolt 55 directly coacts with a keeper plate 56 provided with horizontally disposed slots 57 in which are mounted clamping bolts 58 that are, in turn, mounted in vertical slots 59 formed in the supporting frame 23.

Each track is provided with an opening 60 registering with the opening 61 in the keeper plate. The horizontal wall 62 and the vertical wall 63 of the keeper plate opening 61 are so disposed that when the bolts 58 are properly adjusted in the slots 57 and 59, they will have the desired cam action with the horizontal cam face 64 and the vertical cam face 65 of the bolts 55.

The coaction between the walls 62 and 63 and the cam faces 64 and 65 is such that the door panels are simultaneously given movement in two directions, that is, horizontally and vertically, to bring about a tight fitting action between the panels of the door and the door frame, and between the lower edge of the door and the ground base.

For the purpose of giving the desired sliding movements to the bolts 55 there is provided an actuator 66 consisting of a link 67 having pivoted connections 68 with the rods 69 that are connected to the bolts, the rods being slidably mounted in the guide bearings 70 arranged contiguous to the keeper plates 56. The link 67 is mounted on a shaft 71 that in turn has secured thereto an interior handle 72 and an exterior handle 73 for the manual operation thereof. The link 67 is further provided with notches 74 adjustably related with the lock bolt 75 of any suitable form of lock 76. Due to the arrangement and construction of the notches and their coaction with the lock bolt 75, the latching bolts 55 may be effectively locked in a number of adjusted positions, thereby compensating for any irregularities in construction and assemblage of the parts of the lock, and sliding movements of the door in the use thereof.

To complete the invention, there is provided a lifting mechanism 77 consisting of cables 78 secured to the door panels and each travelling over pulleys 79, with one of the pulleys connected to a coil spring 81, the other end of which is secured to the supporting frame 23. In installing the invention, the rollers 22 are arranged to travel in the pair of guide tracks so that the panels may be flexed relative to each other and caused to travel horizontally and vertically. In the movement of the door panels towards closed position, the wedging action between the closing device 35 and the inclined portion of the track 26 will force the lower portion of the door towards the door frame, and this closing action of the lower portion of the door is effectively increased to assure tight closing action of the door frame through the manipulation of the manually operated locking device which, when operated, gives further downward movement to the door, to in-

crease the cam action between the closing device 35 and the inclined portion 36 and further forces the door horizontally towards the frame. This is accomplished through the arrangement of the cam faces of the latching bolts and their coaction with the walls of the locking plates in the manner hereinbefore set forth. 5

I am aware of the fact that locking devices have been heretofore used with garage doors, but their designs are such as to provide only horizontal 10 displacement of the door, whereas my locking device is so designed as to provide not only horizontal displacement of the door but also vertical displacement so that the door may be simultaneously moved into closed position with the frame 15 and also into engagement with the ground base. I am also of the opinion that I am the first to construct the locking device in the novel manner above set forth, and to associate the same with a self acting closing device whereby the closing 20 action of the latter may be manually increased in the final closing of the door.

What I claim is:

In an overhead garage door movable on guide tracks to an initial closing position and then to a 25 final closing position towards the door frame and towards the ground, a mechanism for moving the door from its initial closing to its final closing position comprising: devices slidably carried by the door and each having two right angularly 30 disposed camming surfaces, one of said surfaces being disposed at an angle to the door frame and the other of said surfaces being disposed at an angle to the ground; means including elements mounted in the tracks and positioned thereon 35 to be engaged by said devices when the door reaches its initial closing position and to coact with the camming surfaces of said devices for simultaneously urging the door towards the frame and towards the ground, thus moving said door 40 from its initial closing position to its final closing position; and means associated with said elements for their vertical and horizontal positioning with respect to said devices whereby to regulate the cam actions of the latter in simultaneously 45 urging the door towards the frame and towards the ground.

WALLACE E. BAGLEY.
